ILLUMINABLE ADVERTISING SIGN

Richard H. Van Den Berg, Milwaukee, Wis., assignor to
Dimentional Products, Inc., Milwaukee, Wis., a cor-
poration of Wisconsin

Filed Feb. 5, 1960, Ser. No. 59,283

Term of patent 14 years

(Cl. D1—12)

FIG. 1

FIG. 2

FIG. 3

FIG. 4

FIG. 5

Fig. 1 is a front elevational view of an illuminable advertising sign, showing my new design;

Fig. 2 is a right side elevational view, the opposite side being a substantial mirror image thereof;

Fig. 3 is a top plan view;

Fig. 4 is a front perspective view taken from the top and left side thereof; and

Fig. 5 is a rear elevational view thereof.

I claim:

The ornamental design for an illuminable advertising sign, as shown and described.
